UNITED STATES PATENT OFFICE.

DAVID LOCKHART, OF HOQUIAM, WASHINGTON.

WIRE-CLAMP.

SPECIFICATION forming part of Letters Patent No. 734,580, dated July 28, 1903.

Application filed April 25, 1903. Serial No. 154,354. (No model.)

To all whom it may concern:

Be it known that I, DAVID LOCKHART, a citizen of the United States, residing at Hoquiam, in the county of Chehalis and State of Washington, have invented a new and useful Wire-Clamp, of which the following is a specification.

This invention relates to devices employed for clamping wires or small rods or cables and may be employed for various purposes and which may be readily clamped to the wire and disconnected therefrom at any point, and has for its object to simplify and improve devices of this character and produce a device which may be employed for grasping wires or cables of a wide range of sizes without changing the implement or adjusting the parts; and the invention consists in certain novel features of the construction, as hereinafter shown and described, and specified in the claims.

In the drawings illustrative of the invention, in which corresponding parts are denoted by like designating characters, Figure 1 is a side elevation from one side, showing the clamping-jaws distended. Fig. 2 is a side elevation from the opposite side with the clamping-jaws closed. Fig. 3 is a longitudinal sectional view thereof.

The improved device consists of a "head" member (indicated as a whole at 10) having an intermediate offset 11, whereby one of the faces at one end 12 is in alinement with the opposite face 13 at the other end, as indicated in Fig. 3. Pivotedly connected at 14 15 to the inner face of the part 12 of the head member are two oppositely-disposed clamp-lever arms 16 17, curving inwardly when in their withdrawn position and partially encompassing the parts 11 13 of the head member and in transverse alinement with the end 13, as shown. The arms 16 17 are provided with studs 18 19, extending from their free ends. The arms 16 17 are formed with inwardly-projecting gripping-jaws 20 21, having their adjacent faces concaved and serrated or not, as may be preferred, and projecting from the arms 16 17 and extending over the opposite side of the portion 12 of the head member are

two other opposing jaw members 22 23, likewise with their adjacent faces oppositely concaved, each of the two sets of gripping-jaws adapted to enclasp the wire between them.

It will be noted that the gripping-jaw members 20 21 are relatively near the pivots 14 15, so that the "nip" will be short and powerful, while the grip members 22 23 are at a greater distance from the pivot-points, with the nip correspondingly longer and less powerful. The shorter nip will generally be employed for grasping the larger wires or rods or cables, which require a stronger grip, while the longer nip will be employed for smaller wires, which require a less powerful grip. Thus the implement may be quickly adapted to the work required of it, as hereinafter more fully explained.

Pivottally connected at 24 25 to the rear end of the portion 13 of the head member are two lever-arms 26 27, having longitudinal slots 28 29, respectively engaging the studs 18 19 on the clamp-arms 16 17 and connected at their free ends to a ring 30 by links 31 32, as shown. By this simple arrangement it will be obvious that a strain exerted upon the ring 30 will powerfully compress the lever-arms 26 27 and cause them to transmit that force with increased power to the arms 16 17, which in turn will compress any object which may be placed between the jaw members 20 21 or 22 23 with increased force. By this means the pull upon the ring 30 is multiplied by the system of levers before it reaches the gripping-jaws.

The instrument may be constructed simply and inexpensively, while at the same time exerting a very powerful grip upon the wire or cable.

The implement may be employed for any purpose for which such implements are usually employed—such as stringing fence-wires, telegraph or telephone wires, and the like—and will also be found very useful in splicing wire cables in drawing the strand-wires through the apertures formed therein by the marlinespikes.

I do not, however, wish to be limited in any manner in the use of the implement for any

particular purpose and reserve the right to its use for any purpose and in any manner to which it is adapted.

Having thus described the invention, what

5 I claim is—

1. A wire-clamp consisting of a head member, opposing clamp-levers pivotally connected at one end to said head member and with studs extending from their free ends, 10 oppositely-disposed grip-jaws extending from said clamp-levers upon opposite sides of said head member intermediately thereof, lever-arms pivotally connected to the other end of said head member and provided with longitudinal slots movably engaging said studs, and means for forcibly compressing said slotted lever-arms, substantially as specified.

2. A wire-clamp consisting of a head member, opposing clamp-levers pivotally connected at one end to said head member and with studs extending from their free ends, 20 oppositely-disposed grip-jaws extending from said clamp-levers intermediately thereof, lever-arms pivotally connected to the other end of said head member and provided with longitudinal slots movably engaging said studs, and means for forcibly compressing 25

studs, and means for forcibly compressing

said slotted lever-arms, substantially as specified.

3. A wire-clamp consisting of a head member, opposing clamp-levers pivotally connected at one end to said head member and with studs extending from their free ends, oppositely-disposed grip-jaws extending from said clamp-levers upon opposite sides of said head member intermediately thereof, one pair 30 of said jaw members comparatively near the pivoted end of said clamp-levers and the other pair of said jaw members comparatively remote from said pivoted ends of said clamp-levers, lever-arms pivotally connected to the other end of said head member and provided with longitudinal slots movably engaging said studs, and means for forcibly compressing 35 said slotted lever-arms, substantially as specified. 40

In testimony that I claim the foregoing as my own I have hereto affixed my signature in the presence of two witnesses.

DAVID LOCKHART.
